SYRINGE TRAY

Robert J. Waller, Pasadena, Calif., assignor of one-third
to Louis W. Barnett, North Hollywood, Calif., and
one-third to Sidney P. Brooks, San Marino, Calif.

Filed Apr. 3, 1962, Ser. No. 69,569

Term of patent 14 years

(Cl. D83—1)

FIG. 1 is an isometric view showing the top one side and one end of a syringe tray showing my new design;

FIG. 2 is an isometric view of the syringe tray shown inverted; and

FIG. 3 is a plan view thereof.

I claim:

The ornamental design for a syringe tray, substantially as shown.
